corporation of New York

Original application February 1, 1940, Serial No.
316,755, now Patent No. 2,264,984, dated De-
cember 2, 1941. Divided and this application
June 7, 1941, Serial No. 397,024

6 Claims. (Cl. 24—153)

This is a division carved out of application Serial No. 316,755, filed February 1, 1940, which issued December 2, 1941 into Patent No. 2,264,984.

The invention relates to improvements in fasteners and more particularly to a novelty constructed fastener compressor of the type adapted to cooperate with prongs on an associated base to bind papers securely in a file.

An object of the invention is to provide a novel fastener compressor with a hingedly mounted frame of a character to jointly hold spaced prongs of an associated base bent down over the face of the compressor.

Another object is to provide a fastener compressor with a substantially rectangular frame hingedly and slidably connected thereto along one edge in a novel manner to facilitate its being easily and securely locked in position over prongs bent over the top face of the compressor.

Another object is to provide a fastener compressor of the type having a hingedly and slidably mounted prong securing frame, with means to prevent sliding movement of the frame while in its open or unlocked position.

Another object is to provide a fastener compressor of the character described which is not expensive to manufacture and which is easy to operate and efficient in use.

The foregoing and such other objects of the invention as will appear hereinafter as the description proceeds will be more readily understood from a perusal of the following specification, in which reference is made to the accompanying drawing, wherein:

Fig. 1 is a plan view showing the compressor in use with the latching frame closed but unlocked.

Fig. 2 is a transverse sectional view taken on line 2—2 of Fig. 1, showing the latching frame raised, in dotted lines.

Fig. 3 is a plan view similar to Fig. 1, showing the latching frame locked.

Fig. 4 is a transverse sectional view taken on line 4—4 of Fig. 3.

The present invention primarily is concerned with a fastener compressor having a novel latching frame hingedly and slidably mounted along one longitudinal edge thereof readily engageable for movement toward or away from prongs overlying the top face of the compressor; and including novel means embodied in the structure hingedly and slidably connecting the frame to the compressor whereby said frame is readily moved and positively locked in its closed prong securing position.

Referring particularly to the drawing, the fastener compressor consists of a substantially elongated sheet of stiff material 11, such as sheet metal, preferably formed at each end with a recess 12. The compressor is adapted to be used in cooperation with a well known type of base element 13 having spaced bendable prongs 14 adapted to extend through similarly spaced openings in a stack of papers 15. The end portions 10 of the prongs extending through the stack are then bent inwardly toward each other downwardly over and against the top face of the compressor plate 11. The spacing of the prongs 14 and the inside edge of the recesses 12 are substantially identical, consequently the prongs engage in said recesses to prevent lateral shifting of the compressor plate relative thereto.

One longitudinal edge of the compressor plate 11 is folded upwardly and then inwardly to define 20 an elevated longitudinal lip 16. Portions of the lip are cut away at a predetermined distance from each end thereof to provide notches 17 and thereby define three lip sections 18, 19 and 21. The section 18 is rolled over inwardly and downwardly to provide a bearing element to receive a longitudinally extending end portion 22 of the latch frame 23 mounted upon the compressor. The other end portion 24 of the latch frame 23 is in the same plane and extends in the 30 same direction as the end portion 22. It is journaled in a bearing element 25 preferably formed by rolling an end portion of the intermediate lip section 19 downwardly in a manner similar to the formation of bearing element 22.

35 The latch frame 23 preferably is formed of substantially stiff wire and includes transverse portions 26 and a longitudinally extending medial portion 27. With the latch in the position illustrated in Fig. 1, its transverse portions 26 align 40 with the notches 17 and it is free to be swung, from the position shown, upwardly into a substantially vertical position as illustrated in dotted lines in Fig. 2. While in its down or closed position, the longitudinal portion 27 of the latch 45 overlies the bent over prongs 14. Because the prongs normally tend to straighten, due to the inherent resilience of their material, means therefore necessarily is provided to prevent undesirable free swinging of the latch frame 23.

50 Accordingly, the latch frame 23 is shiftable longitudinally into a position substantially as shown in Fig. 3 whereby its transverse portions 26 are positioned beneath the elevated lip 16 constituting the major part of the intermediate 55 portion 19 and a part of the end portion 21.

Longitudinal shifting of the latch frame 23, in the direction to lock said frame in its down or closed position, preferably is limited by striking the outer or extreme end of the lip portion 21 downwardly, as at 28. While said latch frame is in its elevated unlocked position, shifting is prevented by abutment of the transverse portions 26 of the latch frame with the edges of the notches 17.

It is evident that the instant structure embodies a hingedly mounted latch frame which is readily locked in closed position over the bent down prongs merely by sliding said latch frame longitudinally a relatively short distance. Of particular importance are the structural features which afford mounting and locking of the latch frame along one longitudinal edge of the compressor plate. This leaves the opposite edge of the compressor plate free of any projection, rib or other objectionable element which might tend to prevent or interfere with ready access to the prongs to effect their being bent or straightened to attach or remove the compressor plate from the stack.

Although an exemplary embodiment of the present invention is illustrated and described in detail, it is to be understood that the invention may embody a variety of modifications in detail structure without departing from the spirit of the invention or the scope of the appended claims.

I claim:

1. A fastener compressor comprising, in combination, an elongated plate adapted to have prongs bent down over its ends inwardly against one face, a frame, a slideable hinged connection joining one edge of said frame to one edge of said plate, and elevated lips on the said edge of the plate arranged to overhang a portion of the frame when the latter is positioned to overlie the prongs and shifted longitudinally to lock said frame against movement from over said prongs.

2. A fastener compressor comprising, in combination, an elongated plate adapted to have prongs bent down over its ends inwardly against one face, a frame having a hinged and longitudinally slideable connection with said plate, said frame being movable from a substantially vertical position downwardly against said prongs, and means on said plate for engaging and hold-

ing the frame against said prongs when said frame is moved longitudinally in one direction, said means engaging the frame to prevent longitudinal movement thereof while in said substantially vertical position.

3. A fastener compressor comprising, in combination, an elongated plate adapted to have prongs bent down over its ends inwardly against one face, an elongated frame, a slideable hinged connection joining one longitudinal edge of said frame to one longitudinal edge of said plate, said frame being hingedly movable into a position to overlie the bent prongs, and means in said hinged connection effective upon longitudinal sliding of the frame to co-act with a portion of said frame and lock it down against said prongs.

4. A fastener compressor comprising, in combination, an elongated plate adapted to have prongs bent down over its ends inwardly against one face, a frame substantially in the form of a rectangular loop having one longitudinal side portion hingedly and slideably connected with one longitudinal edge of said plate for swinging movement toward and away from said plate, and means on said longitudinal plate edge arranged to overlie transverse end portions of said loop to hold it down against said prongs when said loop is moved longitudinally in one direction.

5. A fastener compressor comprising, in combination, an elongated plate adapted to have prongs bent down inwardly against its top face, a frame having a hinged and longitudinally slideable permanent connection with one edge of said plate, and elevated lips on said plate edge to overlie the frame and hold it down against said prongs when said frame is moved longitudinally in one direction.

6. A fastener compressor comprising, in combination, an elongated plate adapted to have prongs bent down over its ends inwardly against one face, a frame, a slideable hinged connection joining one edge of said frame to one edge of said plate whereby the frame may be swung toward or away from said plate, and means in said hinged connection effective upon longitudinal sliding of the frame to lock said frame down against said prongs.

EMIL KERN.
